TOY ANIMAL FIGURE

George I. Polakov, New York, N. Y.

Application April 8, 1950, Serial No. 9,062

Term of patent 7 years

(Cl. D34—2)

To all whom it may concern:

Be it known that I, George I. Polakov, a citizen of the United States of America, residing at New York, in the county of New York and State of New York, have invented a new, original, and ornamental Design for a Toy Animal Figure, of which the following is a specification, reference being made to the accompanying drawing, forming a part thereof.

Fig. 1 is a side elevational view of a toy animal figure, showing my new design;

Fig. 2 is a front elevational view of the toy animal figure shown in Fig. 1; and

Fig. 3 is a rear elevational view of the toy animal figure shown in Fig. 1.

The essential features of my design reside in the portions shown in full lines.

I claim:

The ornamental design for a toy animal figure, substantially as shown and described.

GEORGE I. POLAKOV.
